[57] CLAIM

The ornamental design for an automobile tire, as shown
and described.

DESCRIPTION

FIG. 1 is a perspective view of an automobile tire showing
my new design it being understood that the tread
pattern is repeated uniformly throughout the circumference
of the tire and the opposite side is the same as that
shown;

FIG. 2 is a front elevational view thereof; and

FIG. 3 is a side elevational view thereof.

FIG. 1

FIG. 2

FIG. 3
